A. O. BRILL.
SUSPENSION CAR JACK.
APPLICATION FILED JULY 6, 1908.

909,535.

Patented Jan. 12, 1909.

UNITED STATES PATENT OFFICE.

AUSTIN O. BRILL, OF ZANESVILLE, OHIO.

SUSPENSION CAR-JACK.

No. 909,535.

Specification of Letters Patent.

Patented Jan. 12, 1909.

Application filed July 6, 1908. Serial No. 442,004.

To all whom it may concern:

Be it known that I, AUSTIN O. BRILL, a citizen of the United States of America, and resident of Zanesville, county of Muskingum, 5 and State of Ohio, have invented certain new and useful Improvements in Suspension Car-Jacks, of which the following is a specification.

This invention relates to improvements in 10 car-jacks, and more particularly to a suspension-jack whereby the journal-boxes of railway-cars may be raised for effecting the removal and insertion of the brasses.

The object of the invention is to provide a 15 simple, strong, durable and efficient device whereby the journal-box of a railway-car may be quickly and conveniently raised to permit of the removal and insertion of the brasses.

20 A further object is to provide a device of the character mentioned which is adapted to be supported or sustained by the car-wheel whose brasses or bearings are to be removed, thereby avoiding or dispensing with the 25 necessity for securing at the roadbed a solid support or foundation such as is required when jacks of the ordinary pedestal type are employed.

With these and other objects in view, all 30 of which will hereinafter be made apparent, the invention finally consists in the particular construction, arrangement and combination of parts which will hereinafter be fully described, reference being had to the accompanying drawing, forming a part of this 35 specification, in which—

Figure 1 is a side elevation of the invention, showing it as it appears when applied to a car-wheel, some of the parts being 40 shown sectioned or broken away; Fig. 2 is a section on the line 2—2, Fig. 1; Fig. 3 is a section on the line 3—3, Fig. 1; Fig. 4 is a perspective view of the suspension bracket, a portion of one arm being broken away; 45 and Fig. 5 is a similar view of the cross-bar.

Referring to said drawing, in which like 50 reference characters designate like parts throughout the several views—1 indicates a car-wheel, 2 the axle, 3 the journal-box, and 4 the brasses which rest upon the axle within the journal-box, all being of an ordinary construction.

The lifting mechanism comprises, essentially, a suspension-bracket 5 adapted to 55 engage and receive support from a car-wheel, and adjustable connections between said

bracket and the journal box whereby the latter may be elevated. Said suspension-bracket 5 consists of a body portion 6, a pair of divergent integral arms 7 having hooks 8 60 on their outer ends adapted to clutch the flange 9 of the car-wheel 1, and an integral downwardly and rearwardly inclined leg or brace 10 adapted to rest against the face of the wheel above and adjacent to the journal- 65 box 3.

Supported by a hand-wheel 11 whose hub rests upon the body portion 6 of the suspension-bracket at each side of a longitudinal slot 12 provided in said body portion is a 70 lifting-screw 13 which is adjustable along said slot, adjustment being necessary in order to adapt the device for use in connection with journal-boxes of different sizes or types. The lower end of said lifting-screw has 75 swiveled thereto or thereon a clevis 14 in which is pivotally supported a cross-bar 15. Fixed to one end of said cross-bar is one end of a chain 16 which is adapted to be passed down around the journal-box and 80 have its opposite end inserted in an appropriate slot 17 provided in the opposite end of said cross-bar, where it is securely held against accidental displacement. The employment of a chain, such as is herein shown, 85 whose links are so formed as to be readily gripped by the parallel members 15' formed by the provision of the slot 17 renders unnecessary the use of mechanism whereby adjustment may be secured to compensate for 90 journal-boxes of various sizes and for car-wheels of various heights.

In operation, the suspension-bracket is mounted upon the wheel with the flat bearing portion of each arm 7 resting upon the 95 tread portion of the wheel, with the hooks 8 in clutching engagement with the wheel flange, and with the leg or brace 10 in supporting engagement with the face of the wheel. In this position the two arms 7 engage the wheel at opposite sides and at equal distances from the vertical median line thereof, thus effectually preventing lateral movement or any tendency on the part of the bracket to sway. The lifting-screw 13 is 100 then slipped along the slot 12 to a point directly over that part of the journal-box which is to be engaged by the chain 16, and the said chain is looped around said box. Then, by turning the hand-wheel 11, whose 110 hub is in threaded engagement with said screw, the journal-box is raised, freeing the

brasses from the weight of the car, and thus permitting the same to be removed and replaced.

Mounted in a threaded hole 18 in the end 5 of an integral extension 19 of the body portion 6 or the suspension-bracket is a vertical screw 20 which carries upon its lower end a swiveted clevis 21 to which is pivoted a curved supporting-bar 22 adapted to engage 10 and receive support from the end of the car-axle 2. Said bar has its free end pointed so that it readily engages the usual socket or centering cavity 23 in the end of the axle. As is apparent, this supporting-bar 15 22 with its correlated parts serves as a brace whereby the outer end of the supporting-bracket 5 may be additionally braced or supported when the latter is subjected to severe strain; however, this may be entirely omitted, if desired. For adjusting the supporting-bar, a small hand-wheel 24 is fixed upon the screw 20 above the swivel joint whereby the latter may be turned to adjust its elevation.

25 The supporting-bracket is made heavy in order to effectually withstand the strains to which it is subjected.

Having thus described my invention, what I claim as new, and desire to secure by Letters Patent, is—

30 1. In a car journal box lifting mechanism, a supporting bracket consisting of a body portion having a pair of divergent arms adapted to engage and receive support from a car wheel, and a brace adapted to engage the face of the car wheel, and adjustable connections between the supporting bracket and journal box whereby the latter can be raised.

40 2. In a car journal box lifting mechanism, a supporting bracket consisting of a body portion, a pair of integral divergent arms having supporting hooks adapted to engage and receive support from the car wheel, and a brace adapted to engage the face of the car wheel, a lifting screw supported by said bracket, means for connecting said screw to the journal box, and means whereby said screw may be raised with relation to said bracket.

50 3. A car journal box lifting mechanism consisting of a pair of divergent arms adapted for supporting engagement with a car wheel on opposite sides of a vertical median

line therethrough, a body formed integral 55 with said arms, a supporting leg, a lifting screw adjustably mounted on said body portion, connections between said screw and the journal box whereby the latter is raised when said screw is raised, and means for 60 elevating said screw.

4. A car journal box lifting mechanism consisting of a pair of divergent arms adapted for supporting engagement with a car wheel on opposite sides of a vertical median 65 line therethrough, a body formed integral with said arms, a supporting leg, a lifting screw supported by said body portion, connections between said screw and the journal box whereby the latter is elevated when said 70 screw is raised, means for elevating said screw, and means carried by the outer end of said bracket and adapted to receive support from the car axle whereby said outer end of the bracket is braced.

75 5. A car journal box lifting mechanism consisting of a pair of divergent arms adapted for supporting engagement with a car wheel on opposite sides of a vertical median 80 line therethrough, a body formed integral with said arms, a supporting leg, a lifting screw adjustably supported by said body portion, connections between said screw and the journal box whereby the latter is elevated when said screw is raised, means for 85 elevating said screw, a second adjustable screw carried by the bracket, and a supporting bar connected to said screw and adapted to engage the car axle for bracing the outer end of said bracket.

90 6. In a device of the character described, the combination with a bracket adapted to receive support from a car wheel, and journal box lifting mechanism sustained by said bracket, of bracing means for the outer end 95 of said bracket, said bracing means comprising a screw which is vertically adjustable with relation to said bracket, and a curved supporting bar swiveled to said screw and adapted to engage the centering cavity in 100 the car axle.

In testimony whereof I affix my signature in presence of two subscribing witnesses.

AUSTIN O. BRILL.
